UNITED STATES PATENT OFFICE.

FREDRICK H. AULD, OF COLUMBUS, OHIO, ASSIGNOR TO FRED H. COZZENS,
OF NEW YORK, N. Y.

PHOTOGRAPHIC-PRINTING APPARATUS.

No. 849,184.

Specification of Letters Patent.

Patented April 2, 1907.

Application filed July 7, 1903. Serial No. 164,510.

To all whom it may concern:

Be it known that I, FREDRICK H. AULD, a citizen of the United States, residing at Columbus, in the county of Franklin and State 5 of Ohio, have invented a certain new and useful Improvement in Photographic-Printing Apparatus, of which the following is a description.

This invention relates to that class of photographic-printing machines wherein a traveling sensitized strip is employed to which intermittent movement is imparted, so as to bring successive portions thereof into operative relation to a negative placed between 15 such strip and the light.

The object of the invention is to produce a simple, durable, compact, and reliable mechanism whereby a large number of prints may be produced at high speed.

20 A further object is to provide efficient and reliable means for moving the traveling sensitized strip step by step for the successive exposures to the light and for holding the exposed portions thereof during the intervals of exposure motionless.

A further object is to provide simple but effective mechanism for exposing such strip to the action of the light to permit the printing operation to take place.

25 A further object is to provide automatically-operating mechanism for positively determining or limiting the intervals of exposure of the sensitized strip.

A further object is to provide registering 30 mechanism whereby the number of sections of sensitized paper successively exposed may be registered and indicated.

A further object is to provide a machine of the character indicated which shall be automatic with respect to the several features 35 above stated, a single source of power being employed to drive all the movable parts.

A preferred form of the invention is illustrated in the accompanying drawings, in 40 which—

Figure 1 is a side elevation, the ends of the frame carrying the sensitized-strip rolls being broken away. Fig. 2 is a central vertical section on a smaller scale and illustrating the 45 rolls last referred to in operative position. Fig. 3 is a plan view on the same scale as Fig. 1, the ends of the frame being, as in Fig. 1, broken away and the hood containing the light and shutter mechanism being removed.

Fig. 4 is a side elevation showing a portion 55 of the machine on the side opposite that shown in Fig. 1, particularly the mechanism for operating the shutters and the provision for moving the hood in which such shutters are contained upon its hinges. Figs. 5 and 60 6 are detail views illustrating portions of the recording mechanism, hereinafter to be referred to. Fig. 7 is an end elevation, partly in section, of the worm mechanism shown in elevation in Fig. 1 and in top plan in Fig. 3 65 for driving the dial of the exposure-determining device. Fig. 8 is a central horizontal section of the exposure-determining device and connected mechanism on the line 8-8, Fig. 1. Fig. 9 is an end elevation on the line 70 9-9; Fig. 1, one of the rolls driving the sensitized strip not being shown; and Fig. 10 is a detail, hereinafter to be referred to, illustrating in side view a portion of the stop mechanism shown in Fig. 9. 75

Referring to these drawings, in which similar letters denote corresponding parts, A A' designate the front and rear members, respectively, of the frame of the machine, in the ends whereof are mounted the sensitized-strip roll B and take-up roll B'. 80

C designates the sensitized strip or film carried upon said roll B and running thence the entire length of the frame to the take-up roll B'. 85

D D' designate guide-rolls (the former being preferably adjustable relatively to the latter) the ends whereof are suitably journaled in the front and rear members A A' of the frame and between which passes the sensitized strip C. After passing these guide-rolls said strip passes through the feed-rolls E F, the ends whereof are also journaled in the front and rear members A A' of the frame, and thence to the take-up roll B'. 90 95

In order to keep the sensitized strip taut during its travel from one to the other of the rolls B B', I employ tension devices G, which are here shown as comprising arms g, pivotally mounted at their upper ends in the front 100 and back members of the frame, and rolls g', joining these arms and under which the sensitized strip passes in its travel from one roll to the other. The tendency of these tension devices is naturally to assume a vertical position, thereby imposing sufficient weight upon the strip to keep the same taut. 105

The feed-roll E, as clearly shown in Fig. 1,

is mounted in a bracket e , through which projects a shaft or pintle e' , the upper end whereof is threaded and here provided with a nut e^2 . A coil-spring e^3 lies below that portion of the bracket e through which projects the shaft or pintle e' , while a coil-spring e^4 lies above such bracket and between the same and said nut e^2 . The object of this construction is to permit vertical adjustment of said feed-roll E to vary its relation to its companion feed-roll F . The trunnions f of the feed-roll F are journaled in the front and rear members $A A'$ of the frame, one of said trunnions extending through the former member of said frame and being provided outside the same with the gear f' meshing with the gear M' , carried by the front member A of the frame and to which movement is communicated in the manner hereinafter to be described.

H designates the exposure-hood. This is here shown as rectangular in shape, and mounted in the upper portion thereof is the electric lamp or other light-giving device H' , suitably connected upon the outside of said hood with source of energy, if current be used as the lighting medium. Within this hood are the shutters $I I'$, pivotally mounted upon shafts i , the ends whereof are journaled in said hood, one end of each projecting through the same to receive the motion whereby said shutters are operated. Said hood H is secured to the frame of the machine by means of hinges h . J designates the negative-frame, in which is mounted in any suitable manner the negative j . The side edges of this frame are provided with rabbets receiving guides j' , carried by strips j^2 , secured to the under side of the hood H . By means of this construction, as clearly shown in Fig. 1, the negative-frame J may be readily withdrawn from operative position for the removal of one negative and the substitution of another.

The mechanism for operating the shutters i is best shown in Fig. 4. The rotary shafts i' , to which the shutters are secured, are provided outside the hood H with gears i' , one meshing with a rack i^2 on a block i^4 and the other with a gear i^7 , which latter meshes with a similar rack i^3 , formed upon a block. These blocks are secured to a reciprocating rod i^5 , passing through bearings i^6 , secured to the exterior of said hood H . By reason of the interposition of gear i^7 reciprocating shaft i^5 operates the shafts i , upon which the shutters are mounted, in opposite directions.

K designates a reciprocating shaft for operating the blocks i^4 , the racks carried thereby, and the gears i' and i^7 of the shutters I . This shaft K passes through an orifice in one of the blocks i^4 and is provided on either side of said block with collars k . Said shaft is also provided at its free end with another collar or stop k' . An operating-lever L is pivoted at l to the rear member A' of the frame,

and its end encircles the shaft K . On either side of the lever L where it encircles said shaft the shaft is provided with coil-springs k^2 for the purpose of operating the racks $i^2 i^3$ and coacting mechanism without jar. It will be noted that the shaft K is in the same plane as that in which the hood H is hinged on the top of the frame. Said shaft K being movable within the block i^4 , it therefore follows that said hood H may be thrown back upon its hinges without interfering with the coaction of said shaft K , the blocks i^4 , the rod i^5 , the racks $i^2 i^3$, and gears i' and i^7 . In other words, after said hood has been thrown back—as, for instance, when it is desired to inspect the interior of the machine—if the machine be in operation the mechanism contained in said hood—to wit, the shutters, their shafts, &c.—will operate in the same manner as when said hood is in working position.

M designates an intermittent shaft, to which movement is imparted in the manner hereinafter described. Said shaft is mounted in the front and rear members $A A'$ of the frame both ends projecting through the frame and the rear end being provided with mechanism for operating the shutters through the medium of the lever L . This mechanism comprises a pulley m , with which coacts a belt or cord m' , which cord also coacts with a pulley b' , carried by the end of the shaft of the take-up roll B' . Also mounted upon said shaft M is a cam m^2 , provided on its inner face with a stud m^3 . The periphery of said cam is provided with a notch or depression m^4 , with which coacts a roller m^5 , carried at the end of the fork l' of the lever L . Said lever L is also provided with a fork l^2 , with which coacts the stud m^3 of said cam m^2 . Normally the roller m^5 coacts with the continuously-curved periphery of the cam m^2 . Normally also the stud m^3 and fork l^2 are not in operative relation. When during the rotation of said cam m^2 the stud m^3 coacts with the fork l^2 , the lever L is rocked upon its pivot l , thereby moving the free end of said lever L toward the right, Fig. 4, and in turn moving the racks $i^2 i^3$ and causing the operation of the gears i^7 of the shutters $I I'$. The parts just described are so proportioned and arranged as that the roller m^5 will enter the notch or depression m^4 of the cam m^2 at the moment that the free end of the oscillating lever L reaches the extreme limit of its movement in one direction. At this moment the intermittent shaft M comes to a stop, thereby holding the shutters in open position. When movement of the intermittent shaft M is resumed, the roller m^5 rides up on the periphery of the cam m^2 , and the stud m^3 passes out of engagement with the fork l^2 , thereby rocking the free end of the lever L in reverse direction and causing the shutters to be closed thereby.

The intermittent shaft M is provided with a gear M', to which movement is communicated in the manner hereinafter described. The forward end of said intermittent shaft M is provided with two mutilated gears M² M³, the former being provided with teeth over preferably about a third of its periphery and the latter being toothed over a greater portion of its periphery.

10 The gear M² is provided with an elongated slot M⁴, through which projects a bolt M⁵ on the gear M³, having a nut thereon by means whereof said gears may be locked rigidly together.

15 M⁷ designates a gear mounted upon a shaft secured to the member A of the frame and of about the same breadth as the combined gears M² M³, said gear M⁷ being in operative relation to said gears M² M³. Said gear M⁷ 20 coacts with the gear f', whereby movement is communicated to the feed-rolls F E, as hereinbefore described. The object in using the two gears M² M³ on the intermittent shaft M is to vary the extent of movement which shall be imparted to the sensitized strip by means of the feed-rolls E F. The minimum movement is determined by the larger toothed portion of the periphery of the gear M³. From the movement imparted by

25 this toothed portion the movement imparted to the rolls E F may be very considerably increased by adding to the effective toothed surface which coacts with the gear M⁷ the toothed surface of the adjacent gear M², the gear M⁷ being, as above stated, broad enough to cover and coact with both said gears M² and M³.

30 For instance, in Fig. 9 the movement of the intermittent shaft M will as soon as the first tooth upon the gear M³ comes into contact with the gear M⁷ start the latter in its rotary movement. Should it be desired to increase such rotary movement of the gear M⁷, and thereby draw the sensitized strip a longer distance, it is only necessary to

35 move the gears M² M³ relatively to each other (after loosening the nut on bolt M⁵) and to extend the toothed portion of the gear M² beyond the toothed portion of the gear M³, the teeth of both wheels being, however, in alignment when the gears are clamped together.

40 In other words, a variable throw is secured by this means.

N designates a lock for the gear M⁷. This lock is provided with a tooth n, coacting with 45 said gear, and is pivoted at n', a leaf-spring n² being employed having a tendency to throw the tooth n out of engagement with said gear M⁷. Beyond the pivotal point n' said lock N is provided with an arm n³, coacting with a 50 cam n⁴, carried by a collar n⁵, mounted upon the intermittent shaft M. The cam n⁴ is so arranged on the shaft M as that after the toothed portions of the peripheries of the gears M² M³ have passed the gear M⁷ and 55 when therefore said gear M⁷ comes to a rest

said cam n⁴ will operate the lock N to throw the tooth n into engagement with the teeth of said gear M⁷ to lock the same rigidly in position and preclude further movement. It will therefore be seen that the intermittent 70 movement of the shaft M imparts a correspondingly-intermittent movement to the sensitized strip C and that owing to the connection between the pulleys m and b' the take-up roll B' is simultaneously operated so 75 as to wind the strip so taken up about the same. Of course as this operation progresses the diameter of the take-up roll B' will be constantly increasing. The tension with which the belt m' grips said pulleys m 80 and b' is such that as the diameter of said take-up roll increases there will be sufficient slip to prevent a pull upon the take-up roll, which added to the effect of the feed-rolls E F will draw forward a greater portion of the 85 sensitized strip than is required.

In the present embodiment of the invention I have shown a gear O, to which movement is imparted from a suitable source of power and which is the common operating 90 medium of all the moving parts of the apparatus. Movement imparted to this gear O and its shaft operates through the smaller gear o the gear p, mounted on the rear end of the shaft P and outside the member A' of the 95 frame. The shaft P and the mechanism carried thereby and coacting therewith can perhaps best be understood from the horizontal section illustrated in Fig. 8. Said shaft P extends through the entire width of the machine, projecting through the front member A of the frame thereof. It is provided intermediate of the members A A' of the frame with a friction-clutch, here shown as comprising the female member P', secured to 100 said shaft, and male member P², mounted upon a sleeve P³. Between the male member P² and female member P' of the clutch is a coil-spring P⁵, exerting outward pressure to force the members of said clutch out of operative relation. Mounted upon the sleeve P³ 105 is a gear P⁶, which coacts with the gear M' of the intermittent shaft M. Consequently the intermittent movement of said shaft is imparted from the rotary movement of the 110 sleeve P³ and the gear carried thereby.

115 Mounted loosely upon the shaft P is a collar Q, both said collar and said shaft extending through an orifice in the front member A of the frame. Inside the frame said collar Q 120 is provided with a cam q, the inner surface whereof is provided with a lug q', which in operation coacts with another lug q², carried by said member A of the frame. Outside said front member A of the frame the collar 125 Q is provided with a dial-wheel Q', movable thereon and having a toothed periphery, as shown in Fig. 1, and the face of which is provided with a scale indicating, preferably, seconds or parts thereof. An index Q² is also 130

mounted on the collar Q so as to turn therewith and coöperates with the scale on the face of the dial Q'. The outer end of the collar Q is screw-threaded to receive a nut P⁴, between which and the dial Q' the index Q² is confined. By tightening said nut said dial and index may be firmly bound together.

Q³ designates a coil-spring one end whereof is secured to the collar Q, upon which the dial Q' operates, the other end of said spring being secured to a stop Q⁴, carried by the front member A of the frame.

R designates a cam keyed to or formed integral with the sleeve P³, the object whereof will be presently described. Between the cams R and q is a thrust-sleeve R'.

S designates a gear keyed or otherwise secured to the shaft P and meshing with a gear s, carried by the rear member A' of the frame, and this gear s in turn meshes with a gear s', carried by a shaft s², the ends of said shaft being journaled in the front and rear members A A' of the frame. Near its front end the shaft s² is provided with a bevel-gear s³, coacting with a corresponding gear s⁴ at one end of a shaft S'. Also carried by said shaft S' is a gear s⁵, the purpose of which will be presently described. The shaft S' is carried in the bifurcated end of a bracket S², as clearly shown in Fig. 9. The gear s⁵, carried by the shaft S', is in constant operation, the gear S, by means whereof movement is communicated to the shaft s², and therefore indirectly to said gear s⁵, being mounted upon the shaft P, which is in constant operation under the influence of the gear p.

T designates a shaft provided with a worm T', said shaft being journaled in the bifurcated ends t of the pivoted worm-carrier T², which in turn is pivoted at t' upon the shaft S', on which the gear s⁵ is mounted. This device is best shown in Fig. 7. The worm-carrier T² is provided with a depending arm T³, which coacts with the outer face of the cam R. Said outer face of the cam R is provided with a recess r'. The worm T' is normally in operative relation to the toothed periphery of the dial Q', but may be thrown out of such operative relation by the movement of its carrier T² upon the shaft S', upon which it is pivoted. The worm-carrier is provided with a leaf-spring t², the opposite end whereof coöperates with the support S² for the shaft S', the tendency of said spring being to depress the outer end of the worm-carrier T², in which the worm T' is mounted. Upon such depression said worm is brought into operative relation to the dial Q'. It follows that when the depending arm T³ of the worm-carrier is in engagement with the face of the cam R the worm T' is out of engagement with the periphery of the dial Q'. When during the rotation of the cam R the end of the depending arm T³ comes into engagement with the recess r' formed in the outer face of said

cam R, the worm-carrier is tilted upon its pivotal point, (the shaft S'), whereupon the outer end thereof, carrying said worm T', is depressed and brought into coöperative relation with the toothed periphery of the dial Q'. 70

U designates a stop, here shown as consisting of a screw u, having an adjusting-head u', said screw engaging with a lip u² on the front member A of the frame. Coacting with this stop is a lug u³, carried by or formed integral with the dial Q'. When the lug u³ is in engagement with said stop, the dial will be at zero, the position in which it is illustrated in Fig. 1. If now the nut P⁴ be loosened and the index Q² turned relatively to the zero-mark on said dial, the lug q' will be moved away from the lug q² a distance corresponding to the interval between the end of said index Q² and the zero-mark upon said dial. 75

In other words, the relation between said lugs and the relation between the index and the zero-mark on the dial represent the duration of the exposure to which the sensitized strip is subjected. After this adjustment of the index Q² and dial Q' has been effected 80 and movement imparted to the gear p the gears S, s, and s', the shaft s², the bevel-gears s³ and s⁴, and the gear s⁵ are set in continuous operation. At this time the lower end of the depending arm T³ of the worm-carrier is 85

within the recess r' of the cam R and said worm therefore in operative relation to the milled or toothed exterior of the dial Q'. Consequently the continuous movement of the gear s' is transmitted to the shaft T and worm T' and thence to said dial Q', operating to move said dial the distance between zero and the point to which the index Q² has been moved. When said index Q² and dial Q' have been moved to a point where the indicating-mark upon which said index has been brought to rest is in the position in which the zero-mark is shown in Fig. 1, the lugs q' and q² are brought into coaction, thereby moving rearwardly the cam q and the sleeve P³, upon the end of which is mounted the male member P² of the clutch. As the two members of this clutch come together the continuous movement of the shaft P is imparted through said clutch to the sleeve P³, and therefore to the gear P⁶, carried by said sleeve and which, as hereinbefore described, drives the film-operating mechanism. The cam R of course rotates with the sleeve P³. As the recess r' therein passes out of engagement with the lower end of the depending arm T³ the worm-carrier is tilted upon its pivotal point, (the shaft S'), thereby throwing the worm T' and the dial Q' out of operative relation, whereupon the spring Q³ will return said dial and index to starting position. In other words, the shaft s² and the gears carried by and coacting therewith form, in effect, a bypass for the application of power, which, however, is no longer needed when the sleeve 130

P^3 has been pressed rearwardly and the clutch mechanism heretofore described brought into action.

- 5 V designates a cam also mounted upon the sleeve P^3 and, like the cam R, provided with a recess v . With this recess engages a roller v' , formed on the end of an arm V' , carried by a cross-bar A^2 , extending between the members A A' of the frame. Normally and 10 when the clutch is in inoperative position the roller v' occupies a position in the recess v . After the sleeve P^3 has been pressed rearwardly, however, by the coaction of the lugs $q' q^2$ and through the operation of the clutch 15 motion transmitted to the sleeve P^3 , upon which said cam V is mounted, the latter is caused to rotate, whereupon the roller v' passes out of the recess v and rides against the outer face of said cam V. It follows that 20 from this time on and until the recess v and roller v' are again brought into the position in which they are illustrated in Fig. 8 said roller will prevent the sleeve P^3 from moving forwardly and breaking the coaction of the two 25 members of the clutch. In other words, from this time on the coaction of the two members of said clutch and the consequent rotation of the sleeve P^3 are independent of the coaction of the lugs $q' q^2$. 30 I observe here that the movement of the cam q due to the rotation of the worm T' is preferably somewhat slower than the movement of the cams R and V after the clutch has been thrown into operative relation. Due to 35 this, after said sleeve P^3 has been set in operation the worm T' is quickly thrown out of operative relation to the dial Q' and the roller v' as quickly brought into coaction with the face of the cam V to maintain the 40 operative relation between the two parts of the clutch.

- After the clutch has assumed operative position the sleeve P^3 and gear P^6 , carried thereby, will be moved one revolution. 45 When the recess v and roller v' again come into coaction, the spring P^5 forces the members $P' P^2$ of the clutch apart, whereupon the sleeve P^3 and said gear P^6 are again brought to a stop. 50 The gear P^6 , meshing with the gear M' , causes the operation of the intermittent shaft M and the gears carried thereby and coacting therewith, whereby the strip is advanced one step. The first portion of this 55 movement, however, does not effect the movement of the sensitized strip, because of the interval before the gear M^7 coacts with the first tooth of one or the other of the mutilated gears $M^2 M^3$. During this portion of 60 the revolution of the intermittent shaft M the cam m^2 coacts with the forked end of the lever L to open the shutters I through the mechanism heretofore described. The continued operation of the cam m^2 by moving 65 the end of the lever L in the opposite direc-

tion closes the shutters a moment before the coaction of the gear M^7 with the mutilated gears $M^2 M^3$, or one of them, by means whereof motion is transmitted to the feed-rolls. Consequently the remaining portion of the 70 revolution of the shaft M and gears carried thereby is devoted to the operation of drawing forward a section of the sensitized strip to take the place of that which has been exposed. As this is accomplished the cam m^2 75 again assumes the position in which it is illustrated in Fig. 4, the lever L being thereby operated to throw the shutters to open position for the next exposure.

W designates the shaft of the recording 80 and indicating device. This is journaled at each end in the members A A' of the frame, the forward end projecting through the front member A and being here provided with an index w , coacting with a dial W' , secured to 85 the front member A of the frame and having suitable subdivisions and an indicating-slot w^2 . Between the dial W' and the frame A may be arranged visual indicating-wheels x 90 x' , mounted on the rear face of said dial W' . The shaft W outside the frame A is provided with a collar carrying a tooth which coacts with pins formed on one face of the visual indicating-wheel x' . Said wheel x' is provided also with a tooth coacting with notches or recesses in the visual indicating-wheel x . As 95 will be seen, each revolution of the shaft W and each coaction of the tooth carried thereby with one of the pins of the wheel x' will move said wheel x' one step. Each revolution of the wheel x' will move the wheel x one 100 step. Both wheels $x x'$ may be provided with numbers discernible through the slot above referred to. By means of this visual recording device the number of exposures 105 may be readily ascertained. Each subdivision of the dial W' indicates one exposure and the sum thereof one hundred exposures. After one hundred exposures have been made the visual indicating-wheel x' is moved one 110 step, so as to expose the number "1," the cipher on the wheel x being exposed. This operation will be readily understood from the drawing in Fig. 1, in which the recording mechanism is shown as indicating "1421." 115

Intermediate of its ends the recording shaft W is provided with a ratchet W^3 , said ratchet having one hundred teeth corresponding with the one hundred subdivisions on the face of the dial W' . This ratchet and its operating mechanism are illustrated in detail in Fig. 6. Referring to this figure, W^4 designates a pawl mounted upon the cross-bar A^2 of the frame of the machine, the free end thereof coacting with the teeth on said 120 ratchet W^3 . W^5 indicates a second pawl having its free end coacting with the periphery of the ratchet W^3 , its other end being pivoted to one end of a lever W^6 , also pivoted to the cross-bar A^2 of the frame and having its 125 130

free end extended into position to coact with the lug W^7 on the rear face of the cam V . As will be readily understood, each rotation of said cam V will, by elevating the extended end of said lever W^6 and depressing that end carrying the pawl W^5 , move the ratchet W^3 one tooth and through the shaft W the recording mechanism heretofore described.

- Y designates the platen or pressure device 10 for the sensitized strip. The upper surface of this is preferably provided with a layer of felt, plush, or other suitable material in order that said platen may firmly grasp the strip and hold it in contact with the negative-frame 15 and the negative mounted therein. Said platen Y is mounted upon a vertical shaft Y' , carried in a bearing Y^2 , secured to or formed integral with the cross-bar A^2 of the frame. Y^3 designates a bracket secured to the bearing 20 Y^2 and in the bifurcated end of which is pivoted a lever y , one end whereof is provided with a roller y' , coacting with a cam y^2 , carried by a collar y^3 on the sleeve P^3 of the main shaft P. That end of the lever y opposite the roller y' is provided with a screw y^4 , the adjustment whereof will determine the degree of upward movement of the shaft Y' and the platen Y, carried thereby. Obviously upon each rotation of the collar P^3 the 25 cam y^2 will, by engaging with the roller y' , press the said platen upwardly into engaging position. This of course is at that period in the operation of the device when the sensitized strip is immovable and the shutters 30 open for the exposure thereof.

The essential features of the operation of the machine have heretofore been set forth in connection with the description of the construction. It will be obvious that such operation is entirely automatic. After the sensitized strip has been placed in position and its free end connected with the take-up roll B' the hood H (theretofore thrown backward upon its hinge to permit the adjustment of such strip) is adjusted to the position in which it is shown in the drawings and the negative-slide, with the negative therein, inserted. The necessary period of exposure having been predetermined, the nut P^4 is 40 loosened and the index Q^2 moved upon the dial Q' to that subdivision indicating such period of exposure. The mutilated gears M^2 M^3 are then so adjusted relatively to each other as to transmit to the feed-rolls E F sufficient movement to draw forward after each 45 exposure a section of the strip corresponding to the size of the negative or to the portion of the negative printed from. Power being then applied, the exposure-determining device is operated in the manner hereinbefore described, the platen being moved upwardly to clamp the sensitized strip during each period of exposure and downwardly to release said strip and permit it to travel forward to the take-up roll, the exposure regis-

tered and indicated upon the recording device, and at the end of the exposure the shutters closed and the feeding mechanism operated to move the strip forward one step. The operation in addition to being automatic is uniform and continuous, the number of successive exposures and the consequent production of prints from the negative being limited only by the length of the sensitized film upon which such prints are made.

As above explained, the cam q and lug q^2 , the cam V , and roller v' , and the parts associated therewith operate the clutch so as to cause sleeve P^3 to make one complete revolution at equal intervals of time. When sleeve P^3 makes one revolution, it first operates through lever L to close the shutters, then through the mutilated gears to advance the sensitized strip a predetermined distance, and then through lever L to open the shutters again. Also the cam y^2 on sleeve P^3 operates to lower the platen Y just before the sensitized strip is moved and to raise the platen again after the strip has been brought to rest in its new position, so as to hold the strip firmly against the negative during the printing operation. As sleeve P^3 begins its revolution the arm T^3 of the frame T^2 moves out of the recess r' in the cam R, thus carrying the worm T' out of engagement with the worm-wheel formed on the periphery of the dial Q' , and the dial is retracted by spring Q^3 to the position in which the lug thereon engages its stop. As the sleeve nears the completion of its revolution the arm T^3 on frame T^2 again enters the recess r' in cam R and the worm T' is again brought into mesh with the worm-wheel by spring r^2 . The continued operation of the power-shaft actuates the worm T' through the train of gearing, and the index Q^2 and sleeve Q are rotated until the lug q' engages the lug q^2 . The engagement of these two lugs causes movement of sleeve P^3 axially on shaft P against the tension of spring P^5 until the two members of the clutch are in engagement, and when this occurs shaft P drives sleeve P^3 , causing the latter to make one revolution. As soon as sleeve P^3 begins to move it is held in the position in which the two clutch members are in engagement by the roller v' coacting with the cam V ; but when the sleeve P^3 completes one revolution the recess r in cam V' is opposite the roller v' , and spring P^5 then moves sleeve P^3 axially on shaft P a sufficient distance to cause separation of the two clutch members, and thus bring sleeve P^3 to rest. The operation is repeated in this way, the sensitized strip remaining at rest pressed against the negative during a definite interval of time, which interval is adjustable as desired, while the shutters are open and then the shutters being closed the strip advanced and the shutters opened again.

Having now described my invention, what

I claim as new therein, and desire to secure by Letters Patent, is as follows:

1. In printing apparatus, the combination with means for supporting a sensitized strip and a shutter, of a variable exposure-determining device and operable connections between the same and said shutter, substantially as set forth.
2. In printing apparatus, the combination with means for feeding a sensitized strip, of a holding device for said strip, a shutter, a variable exposure-determining device, and operable connections between said determining device, said stop or holding device and said shutter, substantially as set forth.
3. In printing apparatus, the combination with means for supporting a sensitized strip, a shutter, and a platen movable into and out of operative relation to said strip, of mechanism for feeding said strip, a variable exposure-determining device, and coöperative connections between said shutter, said platen, said feeding mechanism and said determining device, substantially as set forth.
4. In printing apparatus, the combination with means for supporting a sensitized strip, a shutter, and a platen movable into and out of operative relation to said strip, of mechanism for feeding said strip, an exposure-determining device, a recording mechanism, and coöperative connections between said shutter, said platen, said feeding mechanism, said determining device and said recording mechanism, substantially as set forth.
5. In printing apparatus, the combination with mechanism for feeding a sensitized strip, of a hinged hood in juxtaposition to which said strip is adapted to travel, a shutter within said hood, and means for operating said shutter in either position of said hood, substantially as set forth.
6. In printing apparatus, the combination with means for feeding a sensitized strip, of a hood in juxtaposition to which said strip is adapted to travel, a two-part shutter within said hood operable by gears upon the outside thereof, racks coacting with said gears, and means connected with said racks for operating said shutter, substantially as set forth.
7. In printing apparatus, the combination with means for feeding a sensitized strip, of a hinged hood in juxtaposition to which said strip is adapted to travel, a two-part shutter within said hood operable by gears upon the outside thereof, connected racks coacting with said gears, one of said racks being pivotally mounted, and means for transmitting motion to said racks to operate said shutter, substantially as set forth.
8. In printing apparatus, the combination with means for feeding a sensitized strip, of a hinged hood in juxtaposition to which said strip is adapted to travel, a two-part shutter within said hood operable by gears upon the outside thereof, connected racks coacting with said gears, one of said racks being pivotally mounted, and means for transmitting motion to said racks to operate said shutter, substantially as set forth.
9. In printing apparatus, the combination with means for feeding a sensitized strip, of a hinged hood, a shutter within the same, mechanism for opening and closing the same, and a detachable negative frame or support intermediate of said shutter and said strip, substantially as set forth.
10. In printing apparatus, the combination with mechanism for feeding a sensitized strip, of a hinged hood, a shutter within the same and a platen, means for operating said shutter and for moving said platen into and out of operative relation to said strip simultaneously, a strip-feeding device, and connections between said means and said device for assuring interdependent operation thereof, substantially as set forth.
11. In printing apparatus, the combination of an intermittent strip-feeding device and adjustable mechanism coacting therewith for determining the extent of the intermittent movements of the strip, substantially as set forth.
12. In printing apparatus, the combination of rolls carrying a sensitized strip, a guiding device for said strip, and a strip-feeding device comprising an intermittently-operated shaft, gears carried thereby for imparting movement to said strip, and means for varying the extent of movement of said strip under the influence of said feeding device, said means including mutilated gears mounted side by side but adjustable relatively to each other, substantially as set forth.
13. In printing apparatus, an exposure-determining device comprising the combination of a rotary shaft, a dial and an index movable one relatively to the other, mechanism operated by said shaft for moving said dial and index relatively, and means dependent upon the extent of relative movement of said dial and index for effecting an exposure, substantially as set forth.
14. In printing apparatus, an exposure-determining device, comprising in combination a rotary shaft, a dial and an index, mechanism intermediate of said shaft and dial for operating the latter, and a retracting device for said dial, substantially as set forth.
15. In printing apparatus, an exposure-determining device comprising the combination of a rotary shaft, a dial and an index, actuating mechanism for said dial, operable connections between said shaft and said actuating mechanism, and means dependent upon the extent of movement of said dial for effecting an exposure, substantially as set forth.
16. In printing apparatus, an exposure-

determining device, comprising in combination a rotary shaft, a dial and an index, a retracting device for said dial, a worm for actuating said dial, and operable connections between said shaft and said worm, substantially as set forth.

17. In printing apparatus, an exposure-determining device, comprising in combination a rotary shaft, a spring-retracted dial, an index, mechanism for actuating said dial, means for throwing said mechanism into and out of operative relation to said dial, and operable connections between said mechanism and said means, substantially as set forth.

18. In printing apparatus, an exposure-determining device, comprising in combination a rotary shaft, a dial and an index, an actuating device for said dial receiving motion from said shaft, and connections between said index and said shaft, whereby the setting of the former will determine the duration of useful operation of the latter, substantially as set forth.

19. In printing apparatus, an exposure-determining device, comprising in combination a rotary shaft, a dial and an index, actuating mechanism for said dial operated by said shaft, a clutch upon said shaft, and a cam controlled by said index and coacting with said clutch to throw the same into operative position, substantially as set forth.

20. In printing apparatus, an exposure-determining device, comprising in combination a rotary shaft, a collar, a dial pivoted on said collar, an index secured to said collar and coacting with said dial, means for actuating said dial, a cam carried by said collar, and a clutch on said shaft adapted to be thrown into operative position by said cam, substantially as set forth.

21. In printing apparatus, an exposure-determining device, comprising in combination a rotary shaft, a sleeve carried thereby, a clutch between said shaft and sleeve, a dial and an index, means for operating said dial, and mechanism controlled by said index for moving said sleeve and thereby throwing said clutch into operative position, substantially as set forth.

22. In printing apparatus, an exposure-determining device, comprising in combination a rotary shaft, a clutch having a clutch member connected to said shaft a dial and an index, mechanism for throwing said clutch into operative position, and means controlled by the position of said index relatively to said dial for predetermining the duration of such operative position, substantially as set forth.

23. In printing apparatus, an exposure-determining device, comprising in combination a rotary shaft, a clutch having a clutch member connected to said shaft, a spring-retracted dial, a stop therefor and an index coacting therewith, means for actuating said

dial as said shaft is actuated, and mechanism brought into operative relation by said actuating means and governed by the position of said index relatively to said dial for throwing said clutch into operative position, substantially as set forth.

24. In printing apparatus, an exposure-determining device, comprising in combination a rotary shaft, a sleeve thereon, a clutch between said shaft and said sleeve, a dial and an index, an actuating device for said dial, and means controlled by said sleeve for throwing said actuating device into and out of operative relation, substantially as set forth.

25. In printing apparatus, an exposure-determining device, comprising in combination a rotary shaft, a sleeve mounted thereon, a clutch between said sleeve and shaft, a dial and an index, an actuating device for said dial operated by said shaft, means for throwing said actuating device into and out of operative relation to said dial, a cam controlled by said index and operated by said actuating device with said dial, and connections between said cam and said clutch for throwing the latter into operative position, substantially as set forth.

26. In printing apparatus, an exposure-determining device, comprising in combination a rotary shaft, a sleeve mounted thereon and carrying a power-transmitting device, a clutch between said shaft and sleeve, a dial and an index, an actuating device for said dial, a cam positioned by said dial and operated by said actuating device to throw said clutch into operative position, and a cam carried by said sleeve and coacting with said actuating device to throw the same into and out of operative position relatively to said dial, substantially as set forth.

27. In printing apparatus, an exposure-determining device, comprising in combination a shaft, a sleeve mounted thereon, a clutch between said sleeve and shaft, a dial and an index, an actuating device for said dial, a cam positioned by said index and operated by said actuating device to throw said clutch into operative position, a cam upon said sleeve controlling the operation of said actuating device, and a second cam upon said sleeve holding said clutch in operative position after such position has been assumed through the operation of the cam first named, substantially as set forth.

28. In printing apparatus, an exposure-determining device, comprising in combination a rotary shaft, a dial and an index, a continuously-operating actuating device for said dial, means for throwing said device into and out of operative relation to said dial, a clutch carried by said shaft, and mechanism for throwing the same intermittently into operative position, substantially as set forth.

29. In printing apparatus, an exposure-

determining device, comprising in combination a rotary shaft, a dial and an index, a continuously-operating actuating device for said dial, means for throwing said device into and out of operative relation to said dial, a clutch carried by said shaft, mechanism for throwing the same intermittently into operative position, and a power-transmitting device operated by said shaft only when said clutch is in said operative position, substantially as set forth.

30. In printing apparatus, the combination with means for supporting a sensitized strip and intermittent feeding mechanism therefor, of a platen coacting with said strip, an exposure-determining device, a dial and an index therefor, and connections between said device, said feeding mechanism and said platen, controlled by said index, substantially as set forth.

31. In printing apparatus, the combination with means for supporting a sensitized strip, intermittent feeding mechanism therefor, a shutter and a platen, of an exposure-determining device, connections between said device, said feeding mechanism, said shutter and said platen, and a dial and an index controlling the movement of said shutter, said platen and said feeding device, substantially as set forth.

32. In printing apparatus, the combination with means for supporting a sensitized strip, of feeding mechanism for the strip, connections to said mechanism for intermittently operating the same, and a lock for said mechanism adapted to preclude movement thereof in either direction, substantially as set forth.

33. In printing apparatus, the combination with a sensitized-strip-supporting device, of feeding mechanism, connections to said mechanism for operating the same intermittently, means for varying the extent of such movement, and locking mechanism thrown to operative position after each strip-feeding operation of said mechanism and coacting with said mechanism to preclude movement thereof in either direction, substantially as set forth.

34. In printing apparatus, the combination with sensitized-strip-feeding mechanism,

of a shaft, a sleeve carried by said shaft, a connection between said sleeve and said feeding mechanism, a clutch between said sleeve and said shaft, a dial and an index, an actuating device for said dial, and means for throwing the same into and out of operative relation thereto, and mechanism controlled by said index for throwing said clutch into operative position and thereby transmitting movement to said feeding mechanism, substantially as set forth.

35. In printing apparatus, the combination with a sensitized-strip-supporting device, a shutter, a feeding device for said strip and mechanism for intermittently operating said feeding device and shutter, of a shaft, a sleeve carried thereby, a power-transmitting device connected with said mechanism, a clutch between said sleeve and said shaft, a dial and an index, an actuating device therefor and means for throwing the same into and out of operative position, and a cam positioned by said index and operated by said actuating device to throw said clutch into operative position and thereby transmit movement to said mechanism for intermittently operating said feeding device and shutter, substantially as set forth.

36. In printing apparatus, the combination with a sensitized-strip-supporting device, a holding device for said strip, a shutter, a feeding device for said strip and means for intermittently operating said feeding device, said stop and said shutter, of a rotary shaft, a sleeve thereon, a clutch between said sleeve and shaft, connections between said sleeve and said mechanism, a dial and an index, an actuating device for said dial operated by said shaft, means for moving said device into and out of operative relation to said dial, and a cam positioned by said index and operated by said actuating device to throw said clutch into operative position, substantially as set forth.

This specification signed and witnessed this 29th day of June, 1903.
